Primary Examiner — Steven J Czyz(74) *Attorney, Agent, or Firm* — Thomas J. Nikolai; DeWitt LLP(57) **CLAIM**

The ornamental design for an umbrella rib, as shown and described.

DESCRIPTION

FIG. 1 is a perspective view of an umbrella rib, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a side view of umbrella rib, shown in an alternate state; and,

FIG. 9 is a perspective view of the umbrella rib shown in use with environment.

The broken lines depict portions of the article and environment that forms no part of the claimed design.
